(57) **CLAIM**

The ornamental design for a goal defending wall, as shown and described.

DESCRIPTION

FIG. 1 is a front elevational view of a goal defending wall, showing my novel design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is a perspective view of the goal defending wal of the present invention, as shown in use with a soccer goal net. The broken lines shown in FIG. 7 are for illustrative purposes only and form no part of the claimed design.
